UNITED STATES PATENT OFFICE

EDWARD S. WOOLRICH, OF CLEVELAND HEIGHTS, OHIO, ASSIGNOR, BY MESNE ASSIGNMENTS, TO FLEXLUME CORPORATION, OF TONAWANDA, NEW YORK, A CORPORATION OF NEW YORK

NEON SIGN

Application filed September 22, 1928. Serial No. 307,686.

This invention relates to neon tube signs and particularly to small signs adapted to be mounted over doorways, windows and the like.

5. The invention has for its object to provide a sign which is portable, which can be quickly set up in any desired location and which can be quickly and easily dismantled for purposes of transportation or repair.

10. A further object is to provide a neon tube sign in which the neon tube can be quickly and easily attached to or detached from its support to permit signs to be changed when desired.

15. A further object is to provide a supporting member for a neon tube sign which is adapted for mounting on a wall bracket.

With the above and other objects in view, the invention may be said to comprise the 20 sign as illustrated in the accompanying drawings hereinafter described and particularly set forth in the appended claims, together with such variations and modifications thereof as will be apparent to one skilled in the art to which the invention appertains.

Reference should be had to the accompanying drawings in which:

Figure 1 is a perspective view showing the sign of the present invention mounted adjacent a doorway.

Fig. 2 is a longitudinal section through the casing from which the sign is supported.

Fig. 3 is a section taken on the line indicated at 3-3 in Fig. 2; and

35. Fig. 4 is a bottom plan view of the sign supporting casing.

As shown in the accompanying drawings, the sign support is in the form of an elongated box or casing 1 which has a top plate 2 formed of suitable insulating material and side walls 3 which may be formed of sheet metal and which are provided at their upper edges with grooves 4 which slidably receive the top plate 2. The bottom of the casing 40 is closed by detachable plates 5 which are held in place by screws 6. The supporting box or casing 1 is adapted to be secured to the under side of the outwardly projecting arm of an angle bracket 7 attached to a wall 45 adjacent a doorway or window as shown in

Fig. 1 of the drawings. The casing 1 also forms a housing for a suitable transformer 8 which is rigidly secured to the top plate 2 and current is supplied to the transformer through wires embedded in an insulated 55 cable 9 extending from the transformer to a suitable socket 10, mounted in the top plate 2 which is adapted to receive the plug 11 of an extension cord 12, which delivers current from a suitable source such as an electric 60 lighting circuit to the sign.

Current is delivered from the transformer 8 to the neon tube sign through wires 13 and 14 which extend from the transformer to sockets 15 which are attached by screws 16 65 to the under side of the top plate 2 adjacent the opposite ends thereof. Each of the sockets 15 has pairs of oppositely disposed spring contact arms 17 extending downwardly therefrom, the arms of each pair having outwardly flaring lower ends 18 and opposed concave faces 19 which are adapted to grip cylindrical electrodes 20 which are attached to the end portions 21 of the neon tubes and which also serve as contact terminals. 70

The sign may be formed by a single neon tube as shown in Fig. 1 or a plurality of tubes may be employed as shown in Fig. 2, the tube or tubes in either case having a luminous portion 22 intermediate the ends 80 thereof bent to form a sign. In case a plurality of tubes are employed intermediate sockets 23 identical with the end sockets 15 are employed to receive the inner ends of the neon tubes, and the intermediate sockets are 85 connected by a wire 24 so that the neon tubes are connected in series. The end portions 21 of the tubes extend laterally from the sign portion thereof in the plane of the sign for a sufficient distance to space the signs below 90 the bottom of the supporting casing 1 and at their upper ends, the supporting portions 21 are bent inwardly and have the cylindrical electrodes 20 attached thereto.

It will be apparent that a neon tube can 95 be quickly and easily inserted in the sockets by pressing the electrodes 20 between the spring contact arms 17 and that the tubes may be readily detached from the sockets by pulling the electrodes 20 downwardly. The 100

bottom plates 5 have suitable apertures 25 through which the upright portions 21 of the tubes extend and it will be apparent that a neon tube sign can be quickly and easily detached from its support and replaced by a different neon tube sign. The mounting of the sign supporting casing upon a wall is a very simple matter since it is only necessary to attach the base plate 2 to the outwardly projecting arm of a suitable wall bracket and the electrical connections for the sign may be quickly made by means of an extension cord.

Furthermore, it is to be understood that the particular form of apparatus shown and described, and the particular procedure set forth, are presented for purposes of explanation and illustration and that various modifications of said apparatus and procedure can be made without departing from my invention as defined in the appended claims.

What I claim is:

1. A neon tube sign comprising a casing, a transformer in said casing, sockets in said casing having opposed spring contact jaws adapted to clamp a cylindrical member between them and connected with said transformer, and a neon tube having upright end portions and an intermediate portion beneath the casing bent to form a sign, each end of said tube having a laterally projecting contact terminal of cylindrical form clamped between the contact jaws of a socket.
- 35 2. A neon tube sign comprising an elongated casing having a top wall and a bottom wall, a transformer in the casing attached to said top wall, longitudinally spaced sockets mounted on the under side of the top wall, each socket comprising a pair of opposed spring contact jaws, a neon tube sign having upright end portions extending through the bottom wall which are bent laterally at their upper ends and an intermediate sign portion beneath the bottom wall, and contact terminals carried by the upper ends of the tubes, and clamped by said jaws, and means for delivering current through said sockets from the transformer to the tube.
- 40 3. A neon tube sign comprising a supporting member having a pair of sockets each composed of spaced spring contact jaws having opposed concave faces, a neon tube having upright end portions and an intermediate portion bent to form a sign, the outer ends of said upright portions being bent laterally and having contact terminals adapted to be clamped between the spring contacts of said sockets, and means for supplying current to said tube through said sockets.
- 45 4. A neon tube sign comprising a casing having a top wall and a bottom wall, a neon tube sign having an intermediate sign portion beneath the casing and upright end portions

extending through the bottom wall, the upper ends of said upright portions being bent laterally and having contact terminals attached thereto, spaced sockets attached to the under side of the top wall of the casing to receive 70 said terminals and support said sign, and means for supplying current to said tube through said sockets.

In testimony whereof I affix my signature.
